HAZARD WARNING LAMP OR THE LIKE

Arthur J. Pulos, Fayetteville, and Douglas R. Cleminshaw,
Syracuse, N.Y.

Application March 23, 1959, Serial No. 55,138

Term of patent 14 years

(Cl. D48—24)

FIG.1

FIG.2

FIG.3

Figure 1 is a front perspective view of a hazard warning lamp embodying our new design;

Figure 2 is a front elevation thereof on a slightly reduced scale; and

Figure 3 is a side elevation thereof as seen from the right of Figure 2.

The side of the article not shown is the same as the side shown, and the rear is substantially plain. The shading on the lower portion of the front lens member represents conventional ribs on the inner surface thereof.

We claim:

The ornamental design for a hazard warning lamp or the like, substantially as shown and described.
